UNITED STATES PATENT OFFICE

WILLIAM RIENKS, OF ROTTERDAM, NETHERLANDS, ASSIGNOR TO U. S. SLICING MACHINE COMPANY, OF LA PORTE, INDIANA, A CORPORATION OF INDIANA

SLICING MACHINE

Application filed May 10, 1928, Serial No. 276,555, and in the Netherlands June 9, 1927.

This invention relates to an actuating device for imparting reciprocating movement to a carriage of sub plate of machines for slicing food.

5 An object of this invention is to replace the expensive gearing usually found in the drive of these machines with a more simplified and economical driving mechanism in which gearing is eliminated.

10 Fig. 1 is a plan view of the machine with parts broken away.

Fig. 2 is an end elevation as viewed from the left of Fig. 1.

Rising from the bed plate 20 are brackets 15 supporting the slide rods 22 and 23 upon which the carriage 1 is slidably mounted. The knife 12 is journaled in a bracket 21 and is driven through the engagement of a ratchet 9 with a chain 10 which in turn drives the 20 chain 11 on the knife sprocket. The ratchet 9 engages the chain 10 only during the movement of the carriage 1 toward the knife, the ratchet sliding idly over the chain in the reverse direction. This arrangement saves the 25 energy that would be wasted in reversing the direction of rotation of the knife at every back and forward movement of the carriage. The carriage is provided with guides 18 to slidably receive a meat table, movable by 30 well known mechanism not shown, toward the plane of the knife. Bearings 13, 14 and 16 are secured to the frame of the machine and in the bearings 13 and 14 is journaled a shaft 2 having a hand wheel 3 secured to its 35 end. The end of the shaft 2 opposite the wheel 3 has an angularly disposed part 2' which may be integral with the shaft 2 or it may be a separately formed element. The bearing 16 alined with the bearings 13 and 40 14 slidingly and rotatably receives the shaft 17. The shaft 17 has an angular disposed end 15 similar to the end 2' on the shaft 2. The faces on the angularly disposed portions 2' and 15 are parallel and extend from opposite sides of the common axis of the shafts 2 and 17. A crank pin 4 is normal to and connects the faces of the offset parts 2' and 15 and on the crank pin 4 is journaled the bearing hub 5 of a connecting rod 6. A pin 45 or roller 7 extends upward from the opposite

end of the rod 6 through a slot 24 in the bed plate 20. The upper end of the roller or pin 7 engages a recess 8 in the carriage 1. The recess 8 is sufficiently long to accommodate the movement of the pin 7 in the direction of the recess, this motion of the pin 7 being due to the rotation of the end of the rod 6 about the common axis of the shafts 2 and 17. The pin pin 7 extends through an arcuate slot 24 formed in the bed plate 20.

When the hand wheel 3 is rotated, the end 5 of the connecting rod 6, in addition to its rotative movement around the axis of the shaft 2 or 17, is constrained to follow the inclination of the faces on the offset parts 2' and 15 since the rod is at all times held parallel with the offset parts 2' and 15. Considering Fig. 1, it will be seen that when the shaft 2 is given another half revolution, the offset parts 2' and 15 will be inclined so as 60 to direct the rod 6 toward the other end of the slot. Revolving the hand wheel 3 therefore causes the carriage 1 to be reciprocated back and forth past the edge of the slicing knife 12.

75 Although I have illustrated a specific embodiment of my invention, I do not wish to be limited to the particular details shown. An effect similar to that obtained in the illustrated apparatus may be attained by securing on the shaft an angular disc co-operating with a lug or roller on the carriage or by mounting upon the shaft a drum which is provided with a helical groove or rib which, however, is closed in itself and which 80 co-85 operates with a pin or groove respectively on the carriage.

I claim:—

1. In combination with a slicing machine having a slicing knife and a carriage, means 90 for moving said carriage past the edge of said knife, said means comprising a driving shaft, an element angularly disposed with respect to said shaft and rotatable thereby, and a single means having operative engagement 95 with said carriage and angularly disposed element to move said carriage past said knife when said shaft is rotated.

2. In combination with a slicing machine having a slicing knife and a carriage, means 100

- for moving said carriage past the edge of said knife, said means comprising a driving shaft, an element angularly disposed with respect to said shaft and rotatable thereby, and 5 a single element connecting said carriage and angularly disposed element to move said carriage past said knife when said shaft is rotated, said last-mentioned means including a pin slidable in a recess in said carriage.
- 10 3. In combination with a slicing machine having a slicing knife and a carriage, means for moving said carriage past the edge of said knife, said means comprising a driving shaft, an element angularly disposed with respect to said shaft and rotatable thereby, and means connecting said carriage and angularly disposed element to move said carriage past said knife when said shaft is rotated, said last-mentioned means including 15 a connecting rod held parallel with said angularly disposed element and having its ends operatively engaging said element and carriage.
- 15 4. In combination with a slicing machine having a slicing knife and a carriage, means for moving said carriage past the edge of said knife, said means comprising a driving shaft, an element angularly disposed with respect to said shaft and rotatable thereby, and 20 means connecting said carriage and angularly disposed element to move said carriage past said knife when said shaft is rotated, said last-mentioned means including a connecting rod held parallel with said angularly disposed element during rotation of said 25 shaft, one end of said rod being formed to engage said element and the other end having a part engaging a recess in said carriage.
- 25 5. In combination with a slicing machine having a slicing knife and a carriage, means for moving said carriage past the edge of said knife, said means comprising a driving shaft, an element angularly disposed with respect to said shaft and rotatable thereby, and 30 a pin extending substantially normal from said element, a connecting rod journaled at one end on said pin and having a connection at its other end with said carriage.
- 35 6. In combination with a slicing machine having a slicing knife and a carriage, means for moving said carriage past the edge of said knife, said means comprising a driving shaft, an element angularly disposed with respect to said shaft and rotatable thereby, a slidingly and rotatably mounted second shaft 40 alined with said first shaft, an element angularly disposed with respect to said second shaft and rotatable thereby, and a connecting rod having one end positioned between 45 said elements and the other end operatively connected with said carriage.
- 50 7. In combination with a slicing machine having a slicing knife and a carriage, means for reciprocating said carriage past the edge of said knife, said means comprising a driv-
- ing shaft having an offset portion angularly disposed with respect to said shaft, a slidably and rotatably mounted second shaft alined with said first shaft, said second shaft having an offset portion parallel with the offset portion on said driving shaft, a crank pin connecting said offset portion, and a connecting rod journaled at one end of said pin and having a part on its other end engaged in an elongated recess in said carriage. 55
8. In combination with a slicing machine having a slicing knife and a carriage, means for moving said carriage past the edge of said knife, said means comprising a driving shaft, an element angularly disposed with respect to said shaft and rotatable thereby, means connecting said carriage and angularly disposed element to move said carriage past said knife when said shaft is rotated, a chain for rotating said knife, and a ratchet 60 extending from said carriage and operatively engaging said chain when said carriage is moved toward said knife.
9. In a slicing machine, the combination with a base, of a carriage movably supported on said base, a knife rotatably supported by said base, and means operative during only a portion of the travel of said carriage to actuate said slicing machine knife. 65
10. In a slicing machine, the combination with a frame, a knife rotatably mounted on said frame, a carriage adapted to be reciprocated past said knife, and means on said carriage adapted to engage means on the frame to rotate said knife while said carriage is moving in one direction only. 70
11. In a slicing machine, the combination with a base member, a knife rotatably supported on said base member, a driving element operatively connected to said knife to 75 rotate the same, and means on said carriage adapted to engage said driving means while the carriage is moving in one direction only. 105
12. A device as claimed in claim 11 in which the driving means for the knife comprises a chain mounted on suitable sprockets on the frame and slicing knife, and the means on the carriage comprises a pawl which is adapted to engage the chain and thereby move said chain as the carriage is moved in one direction, said pawl being free to ride over said chain without actuating the same as the carriage moves in the opposite direction. 110
13. A slicing machine comprising a base member and a work supporting table movably supported thereon, a crank shaft having an angularly offset crank pin mounted on said base member, and a connecting rod rotatably mounted on said crank pin and operatively connected to said table so that rotation of the crank causes reciprocation of said table. 115
14. In a slicing machine, the combination with a base member, a slicing knife rotatably mounted thereon, a carriage mounted to re- 120

ciprocate past said slicing knife, a crank shaft having an angularly offset crank pin mounted on said base member, a connecting rod operatively connected to the crank pin and to the carriage so that rotation of the crank shaft causes the table to reciprocate, and an arcuate slot in said base member, a portion of the operative connection between said connecting rod and said table extending through said arcuate slot.

10 15 A device as claimed in claim 14 in which the operative connection between the connecting rod and the table comprises a pin mounted on said connecting rod and adapted to extend into a slot in said carriage, said pin also extending through said arcuate slot in the base member.

15 20 In testimony whereof I have signed my name to this specification on this 25th day of April, A. D. 1928.
